DESIGN FOR AN ELECTRON DISCHARGE DEVICE

Terry M. Shrader, West Summit, N. J., assignor,
by mesne assignments, to Radio Corporation
of America, New York, N. Y., a corporation of
Delaware

Application April 20, 1935, Serial No. 56,476

Term of patent 14 years

To all whom it may concern:

Be it known that I, Terry M. Shrader, a citizen
of the United States, residing at West Summit,
in the county of Union, State of New Jersey, have
invented a new, original, and ornamental design
for an Electron Discharge Device, of which the
following is a specification, reference being had
to the accompanying drawing, forming a part
thereof.

Figure 1 is a perspective view of an electron dis-
charge device embodying my new design; and
Figure 2 is a bottom view of an electron dis-
charge device shown in Figure 1.

The present design comprises as its principal

and dominating features a cylindrical body por-
tion rounded at its upper rim to merge into a flat
impervious disc, the lower rim of the body por-
tion being flared outwardly and joined to a sec-
ond cylindrical body of larger diameter than said
first-mentioned body and its flared rim, and the
underside of the second-mentioned cylindrical
body having a circle of spaced pins with a larger
central pin.

I claim:

The ornamental design for an electron dis-
charge device substantially as shown and de-
scribed.

TERRY M. SHRADER.
